[57] CLAIM

The ornamental design for a rear entry boot, as shown and described.

DESCRIPTION

FIG. 1 is a top plan view of a rear entry boot showing my new design;

FIG. 2 is a right side view thereof;

FIG. 3 is a bottom plan view thereof;

FIG. 4 is a front view thereof;

FIG. 5 is a rear view thereof;

FIG. 6 is a left side view thereof; and,

FIG. 7 is a view analogous to FIG. 2, but showing a rear flap in an open condition.

FIG. 4

FIG. 5

FIG. 6

FIG. 7
